(57) **CLAIM**

The ornamental design for an in-vehicle position measurement driving guidance system, as shown and described.

DESCRIPTION

FIG. 1 is a front perspective view showing the in-vehicle position measurement driving guidance system in use, where a display unit is deployed.

FIG. 2 is a front view of the in use configuration shown in FIG. 1;

FIG. 3 is a rear view of the in use configuration shown in FIG. 1;

FIG. 4 is a right side view of the in use configuration shown in FIG. 1;

FIG. 5 is a left side view of the in use configuration shown in FIG. 1;

FIG. 6 is a top view of the in use configuration shown in FIG. 1; and,

FIG. 7 is a bottom view of the in use configuration shown in FIG. 1.

The portions indicated in broken lines are for illustrative purposes only and form no part of the claimed design.
